UNITED STATES PATENT OFFICE.

EDWARD W. ISOM, OF WINNETKA, ILLINOIS, AND JOHN E. BELL, OF BROOKLYN, NEW YORK, ASSIGNORS TO SINCLAIR REFINING COMPANY, OF CHICAGO, ILLINOIS, A CORPORATION OF MAINE.

CIRCULATORY CRACKING STILL AND PUMP THEREFOR.

Application filed May 12, 1921. Serial No. 489,036.

Our invention relates more particularly to circulatory pressure stills for cracking petroleum and other heavy hydrocarbons. An example of such form of still is to be seen in Patent No. 1,285,200 granted November 19, 1918, to Sinclair Refining Company. On reference to the drawing of that application it will be seen that the bulk of the oil being processed is contained in a tank exterior to the furnace by which the heat is supplied thereto and circulated from said tank through a series of heating tubes in the furnace and back to the tank. For the most efficient operation of a still of this character it is necessary that the oil being treated be quite rapidly circulated and preferably some positive liquid forcing means such as a pump is employed. As the temperature of the oil is far above its ignition point and it is commonly under a pressure of 4 or 5 atmospheres or even higher, the matter of preventing leakage of the hot inflammable oil presents a serious problem particularly in view of the wide range of temperatures to which the liquid forcing means is subjected.

It is the object of the present invention to provide in such a circulatory pressure still a pump which will satisfactorily meet the conditions referred to above and properly handle the circulation of the hot oil without leakage.

In the accompanying drawings we have shown and in the following specification described a cracking still with a preferred form of pump embodying our invention. It is to be understood, however, that the specific disclosure is for the purpose of exemplification only and that the scope of the invention is defined in the following claims in which we have endeavored to distinguish it from the prior art so far as known to us without however relinquishing or abandoning any portion or feature thereof.

In the drawings accompanying and forming part of this application Fig. 1 is a vertical section of the preferred form of the pump of the invention on the line 1-1 of Fig. 2; Fig. 2 a transverse section thereof on plane of line 2-2 of Fig. 1 looking in the direction of the arrow; Fig. 3 a similar section on the line 3-3 of Fig. 1 looking

in the direction of the arrows; Fig. 4 an end elevation partly in section and Fig. 5 a diagrammatic view in side elevation. Each 55 part is identified by the same reference character wherever it occurs in the several views.

We have chosen for the purpose of illustrating the invention a pump of the rotary piston, two lobed type but it will be apparent from the following description that the invention in its broader aspect is applicable in connection with a great variety of pumps whether of the rotary or reciprocating type. In the particular form of pump 65 shown in the drawings the pump body comprises a body casting 5 containing the pump chamber 6, the inlet connection 9 and the outlet connection 10. Said piston chamber is closed at its ends by the end castings 11 and 12. The pump chamber is oblong as shown in Fig. 2 and formed with semi-cylindrical ends, and the pistons 7 and 8 are arranged to rotate therein, in such close relation with each other and with the walls of the body 70 casting as to constantly form a seal between the inlet and the outlet sides respectively of the pump chamber. The pistons turn oppositely in the directions indicated by the arrows, each piston at each half revolution shutting off a charge of liquid received from the inlet side of the pump between the body of said piston and the corresponding end of the housing and transferring it to the outlet side of the latter. 80 The shafts 15 and 16 on which the pistons are mounted are journalled in end castings 11 and 12 and provided with gears 13 and 14 respectively, which intermesh so that they are driven in unison. One of said shafts 90 extends beyond the casing at 17 and is coupled with any suitable source of power to drive the pump. As thus far described the pump chosen for exemplification of the invention and its operation are well known, 95 the pump being in common use.

Our invention relates to a circulatory pressure cracking still including in combination a circulating pump particularly adapted for handling hot oil under pressure 100 undergoing cracking, for preventing the escape of the hot oil about the driving shaft and for lubricating the moving parts. As the pump is necessarily subjected to ex-

treme variations in temperature the bearings of the shafts must be quite free to avoid binding when heated to the maximum temperature employed and this further complicates the problem. In the apparatus of our invention, the shafts of the circulating pump are fitted loosely in their bearings and provision is made to force relatively cool oil, for example, oil at ordinary temperature, preferably of the kind being processed, through the bearings against the pressure of the hot oil within the pump chamber, thus not only preventing the escape of the hot oil, but thoroughly lubricating the bearings and preventing them from becoming unduly heated.

In the form of circulating pump construction which we have chosen for exemplification, the end castings 11 and 12 are similar and therefore a description of one will suffice for both. Each of these end castings comprises a main body portion 18, see dotted lines Fig. 1, of suitable dimensions to provide for the bearings of the shafts 15 and 16 which are formed therein, and end flanges 19 and 20 arranged at the respective ends of the body portion of the casting and connected by webs 21 certain of which are shown in section in Fig. 1. The main or body casting of the pump is formed with flanges 25, to which the flanges 19 of the end castings are respectively bolted. The body portions of the end castings are respectively formed with suitably spaced bores 22 which receive bushings 23 in which are formed the bearings for the respective shafts 15 and 16 upon which the rotary pistons are keyed. The fit of the shafts in the bushings is sufficiently free to avoid binding at all times, notwithstanding the high temperature to which the pump is subjected by the circulating hot oil and to permit the passage of a thin film of oil about the shafts. The gears 13 and 14 are mounted on the respective shafts beyond one of the end castings and are enclosed in a housing 28, the flange of which is bolted at 29 to the outer flange of said end casting. The shaft by which the pump is driven extends through said housing at 39 where there is formed a packing box 40 containing packing 41 and receiving the gland 42. Openings 35 and 36 are formed in the ends of said housing and receive, respectively, an inlet pipe 37 and an outlet pipe 38 by which cold oil under pressure is supplied to the housing and escapes therefrom. The other end casting is provided with a cap or cover plate which is bolted thereto at 27 and said cover plate is recessed or chambered at 30 and formed with passages 31 and 32 which receive, respectively inlet and outlet pipes 33 and 34 by means of which relatively cold oil is circulated through chamber 30.

As shown diagrammatically in Fig. 5,

which illustrates the circulatory pressure still of the invention, the inlets 33 for supplying oil respectively to the hollow cap plate and the gear housing, are connected to a small pump 44 capable of developing a 70 pressure in excess of that within the main pump chamber. Said pump is connected by pipe 45 to a supply of oil 46 which may be and preferably is the source from which the main body of oil in the still and its connections is supplied. The outlet pipes 34 and 38 may be connected to the main circulating system of the still, the connection in the present instance being shown as made to the outlet pipe 47 from the circulating 80 pump.

During the operation of the pressure cracking still of the invention the main pump is operated to circulate the oil from the still proper or vaporizing tank 48 to and through the heating pipes in the furnace from which the oil returns to tank 48 through pipe 49. The small pump 44 is continuously operated to force a circulation of cold oil from supply tank 46 through chamber 30 in the cap plate 26 and through the gearing housing, the bulk of which oil passes through pipes 34, 38 to the exhaust pipe 47 of the main pump where it mingles with the hot oil. A limited amount of the cold oil, however, is forced through the bearings of the shafts from the chamber in the cap plate and the gear housing respectively, into the main pump chamber where it mingles with the circulating hot oil under pressure after having served to prevent the escape of the hot oil through said bearings and thoroughly lubricated the latter. There is no difficulty in suitably packing the gear housing against the escape of the oil contained therein since the oil therein is relatively cool and the ordinary packing device described suffices for this purpose. But even in the event of the escape of the cold oil, no damage would result as it is far below the 100 temperature of ignition. If desired a sufficient amount of cold oil can be circulated through the chamber 30 and the gear housing to substantially lower the temperature 110 of the bearings of the pump.

In a circulatory pressure cracking still embodying the invention and including a circulating pump of the rotary piston type, in which 2000 gallons per minute of hot oil at a temperature between about 700° F. and 120 800° F. for example, are circulated through the main pump, a flow of about 3 gallons per minute of cool oil, that is oil at ordinary temperatures, into the pump chamber through the pump bearings is sufficient to 125 prevent the escape of hot oil through the pump bearings and to cool and lubricate the pump bearings.

It has been found difficult to operate circulatory pumps in circulatory cracking stills on 130

- account of the deposits of carbon that take place on all parts exposed to the oil circulating through the cracking stills. Such circulating pumps tend to bind and freeze so that they cannot be turned over and have to be dismantled and the carbon cleaned out. It is one of the objects of this invention to provide a pump that is free from this objection when operated in conjunction with a circulatory pressure cracking still and we have found that this can be done in a very simple and satisfactory way. We proportion the impellers or pistons of the pump so that there is a clearance between all moving parts and the moving and stationary parts. When first installed in a circulatory cracking still a pump with such clearness is inefficient on account of the great amount of leakage but we have discovered that by operating it, pumping hot oil containing a large percentage of carbon, the carbon will deposit and if the pump is kept in continuous operation, the carbon so deposited on two surfaces moving relative to each other is ground until it effects a satisfactory seal. As there is a continual grinding action during all the time the pump is in operation the thickness of this carbon deposit determines the resistance or friction of the pump due to this form of seal. When the carbon layer is very thin the shearing action necessary for grinding off the fresh precipitate is excessive and is reduced by increasing the thickness. We generally prefer to allow a clearance of $\frac{1}{4}$ " to $\frac{3}{8}$ " more or less between the pump pistons and the side of the pump casing and a clearance somewhat less between the pistons and the ends of the casing.
- We claim:
1. In a pump for operation on cracked oil containing carbon released during cracking, and in combination with the casing, a pump piston having a clearance of approximately three-eighths inch within the casing whereby the carbon which accumulates on the walls of the casing forms a packing therefor.
  2. In a circulatory oil cracking still having a still proper, heating pipes in a furnace and connections between said still and heating pipes, a circulatory pump arranged to circulate hot oil from said still to and through said heating pipes and back to the still, said pump having loosely fitting bearings and means for forcing relatively cool oil through said bearings into said pump and circulatory system.
  3. In a circulatory oil cracking system a rotary pump having two impellers or pistons, the shafts of said impellers having loosely fitting bearings, gears on one end of each of said shafts within the pump casing beyond the bearings, a compartment for said gears, and means for forcing relatively cool oil into said compartment and thence through the loosely fitting bearings around the shaft into the pump and circulating hot oil.
  4. In the circulatory system of an oil cracking still a rotary pump handling hot oil, said pump having opposed pistons or impellers with a clearance therebetween and between the pistons or impellers and the casing, whereby binding of the impellers is prevented and the formation of a carbon deposit permitted for sealing the action of the impellers in the pump.
  5. In the circulatory system of an oil cracking still a rotary pump having opposed pistons or impellers with a clearance therebetween and between the pistons or impellers and the casing, and a carbon layer on said impellers and casing forming a seal therefor.
  6. In a circulatory oil cracking still system having a vaporizing drum, a heater and a connection between said heater and vaporizing drum, means for discharging hot oil products from said vaporizing drum, means including a pump for returning hot oil products discharged from said vaporizing drum to the heater, said pump having loosely fitting bearings and means for forcing relatively cool oil through said bearings into said pump and circulatory system, and means for maintaining superatmospheric pressure on the hot oil products throughout the system.
